CLAIM

I claim the ornamental design for a cigarette and cigar disposal unit, as shown and described.

DESCRIPTION

FIG. 1 is a front view of a cigarette and cigar disposal unit showing my new design (the rear view appearing identical).

FIG. 2 is a top view thereof.

FIG. 3 is a bottom view thereof.

FIG. 4 is a side view thereof (the opposite side appearing identical); and,

FIG. 5 is a perspective view thereof.
